Primary Examiner — Joseph Kukella*Assistant Examiner* — Breana Copeland(74) *Attorney, Agent, or Firm* — Young Basile Hanlon & MacFarlane, P.C.(57) **CLAIM**

The ornamental design for a camera mount adapter as shown and described.

DESCRIPTION

FIG. 1 is a front, upper, right perspective view of a camera mount adapter of our new design;

FIG. 2 is a front view thereof;

FIG. 3 is a rear view thereof;

FIG. 4 is a right view thereof;

FIG. 5 is a left view thereof;

FIG. 6 is a top view thereof; and,

FIG. 7 is a bottom view thereof.

Broken lines of equal length (e.g., dash-dash) represent unclaimed subject matter and form no part of the claimed design.
